(57) **CLAIM**

The ornamental design for a projector, as shown and described.

DESCRIPTION

FIG. 1 is a rear perspective view of a projector, showing our new design;

FIG. 2 is a front perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a right rear perspective view shown in an alternate configuration;

FIG. 11 is an enlarged detail view of area 11 in FIG. 2;

FIG. 12 is an enlarged detail view of area 12 in FIG. 2;

FIG. 13 is an enlarged detail view of area 13 in FIG. 3; and, FIG. 14 is an enlarged detail view of area 14 in FIG. 3.

The broken lines in the drawings illustrate the portions of the projector, which form no part of the claimed design.

The dash-dot-dash broken lines encircling the enlarged views are for annotative purposes only and form no part of the claim thereof.

1 Claim, 14 Drawing Sheets
